BOILER FEED

Delroy McBride, Twin Falls, Idaho

Application June 28, 1946, Serial No. 680,047

7 Claims. (Cl. 137—101)

1 This invention relates to a means for automatically feeding water to steam boilers.

An object of this invention is to provide a positive means for automatically maintaining a predetermined water level in a boiler which will eliminate all forms of packing glands.

Another object of this invention is to provide a feeder for a boiler wherein the water enters the boiler after equalization of steam pressure in the feeding tank.

A further object of this invention is to provide an improved feeding means including a feeding tank connected to a source of water, and also connected to the boiler, the tank having float operated valve means whereby the steam pressure in the tank will be equalized in order that the water in the tank may gravitantly flow into the boiler.

A further object of this invention is to provide a boiler feeding means of this kind which includes an electrically operated water supply valve which is actuated by float means connected to the boiler so that the water level in the boiler can be maintained at a predetermined level.

A further object of this invention is to provide a feeding means of this kind which will operate on either high or low water pressures and either high or low steam pressures.

With the above and other objects in view, my invention consists in the arrangement, combination and details of construction disclosed in the drawings and specification, and then more particularly pointed out in the appended claims.

In the drawings,

Wherein similar reference characters designate similar parts throughout the respective views,

Figure 1 is a detail side elevation, partly broken away and in perspective, of a boiler and boiler feeding means constructed according to an embodiment of this invention.

Figure 2 is a vertical section taken through the boiler feeding structure showing the structure with the tank substantially empty.

Figure 3 is a view, similar to Figure 2, showing the tank full.

Referring to the drawings, the numeral 10 designates generally a boiler of conventional construction which has a water glass 11 indicating the height of water in the boiler. The boiler 10 has extending from the top thereof a steam outlet 12 which has a valve 13 of conventional construction secured thereto.

In order to provide a means whereby water may be automatically supplied to the tank 18, I have provided a feeding tank 14 which is mounted on

5 a platform or supporting member 15 disposed above the level of the boiler 10. The feeding tank 14 has connected with the bottom thereof an outlet pipe 16 which is connected, as at 17, to the boiler 10. The pipe 16 is inclined to the horizontal so that the water passing through the pipe 16 will freely enter the boiler 10. A rearwardly closing check valve 18 is interposed in the pipe 16 and preferably a second check valve 19 is also interposed in the pipe 16 at a point closely adjacent the feeding tank 14.

The tank 14 includes a cylindrical horizontally disposed wall 20 having a head 21 secured to one end thereof. A second head 22 is secured to the 15 opposite end of the body 20 and is formed with a relatively large opening 23 which is closed by a plate or head 24. The plate or head 24 is detachably secured to the fixed head 22 by fastening members 25. The head 24 has rockably secured to the inner side thereof a lower float 26 which is carried by a pivoted lever 27 pivotally secured as at 28 to the inner side of head 24.

A second or intermediate float 29 is disposed in the feeding tank 14, being fixed to an elongated lever 30 which is pivotally secured as at 31 to the outer end portion of a supporting bar 32 which is fixed relative to the head 24. A third or upper float 33, carried by a supporting lever 34 is disposed above the intermediate float 29 and is rockably mounted as at 35 on an inwardly projecting supporting bracket arm 36 fixed to the inner side of head 24. The lever arm 30 of the intermediate float 29 has projecting downwardly therefrom a foot member 37 which overlies the float 26 so that when the tank 14 is being filled float 26 will initially cause upward movement of float 29 therewith.

In order to assist in the upward movement of the two floats 26 and 29, I have provided a balance lever 38, pivotally mounted as at 39 on the inner portion of supporting arm 32. The balance arm 38 is connected at its inner end by means of a link 40 to the inner end portion of the float lever 30. The rear end of the balance lever or arm 38 has a weight 41 mounted thereon and adapted to be lengthwise adjusted to provide the necessary balance in order that the two floats 26 and 29 may freely rise with the filling of the tank with water.

In order to hold the two floats 26 and 29 against upward movement until the tank 14 becomes substantially filled with water, I have provided a locking member 42 which is carried by the pivot member 35 and is adapted, during the initial filling of the tank 14, to engage a roller

43 which is carried by an ear 44 fixed to the float arm or lever 30. The locking member 42 has a shoe 45 at its lower end which is adapted to engage the roller 43 during the initial filling of the tank so as to thereby lock the two floats 26 and 29 against initial upward movement.

When the tank 14 becomes substantially filled with water, float 33 will rise and a link 46 pivotally connected at one end to the float arm 34 is also slidably connected to a pin 47 carried by the locking member 42 in order that when the float 33 rises to a predetermined point, the locking member 42 will be swung upwardly and out of locking engagement with roller 43 so that float arm 30 may freely rise under the buoyance of float 29.

The tank 14 has connected to the upper portion thereof a steam valve 48 which communicates with the interior of tank 14 and is connected by means of a pipe 49 to the boiler 10. The valve 48 includes a vertically movable valve plug stem 50 which, in the lowered position of the floats, is adapted to close the valve 48 against the entrance of steam in the upper portion of tank 14. The valve 48 is moved to an open position when tank 14 is substantially filled by means of vertically movable slide rod 51 carried by a guide 52 which is fixed to the bracket arm 36. The rod 51 is formed with a right angularly disposed lower end 53 which loosely engages in the slot 54 formed in the downwardly projecting ear 55 formed as an integral part to the float arm or lever 30.

The rod 51 has fixed on its upper end a slotted bar 56 within which the lower end of the valve stem 50 loosely engages. In this manner the vertical movement of rod 50 under the rise or fall of the intermediate float 29 will cause vertical movement of the valve stem 50 to either open or close the valve 48.

In order to provide for the exhaust of steam or fluid which may be in the upper portion of the tank 10 during the filling of the tank, I have provided an exhaust valve 57 which is interposed in an exhaust pipe 58. The pipe 58 is connected to the upper portion of tank 14 and the valve 57 is normally urged to an open position by means of a spring 59.

A second arm 60 is carried by the upper end portion of rod 51 and with which the stem 61 of the valve 57 is connected so that when rod 51 is moved upwardly to a position where the steam valve 48 will be open, the exhaust valve 57 will at this time be closed. This will prevent the release of any steam pressure on top of the water which is in the tank 14 during the emptying of the tank of water into the boiler 10. The supporting bar or arm 32 has extending downwardly therefrom a stop member 62 which is adapted to be engaged by the lever arm 30 when this arm is in its lowermost position.

A second stop lug 63 is carried by the arm 32 and is adapted to limit the upward movement of the float arm 30 after this arm has been released by movement of the locking member 42 under the action of the rise of the upper float 33. A supporting arm 64 extends upwardly from the arm 32 and has a right angularly disposed stop member 65 which serves as a rest or stop to limit the downward movement of the upper float lever or arm 34. When the lever arm 30 rises after being released from the locking member 42, a second locking member 66 which is pivotally carried by the float lever 30 is adapted to engage a roller 67. The roller 67 is carried by an ear

68 fixed to the lower float lever arm 27 so that the intermediate valve operating float 29 will be prevented from closing the steam valve 48 and opening the exhaust valve 57 until the tank 14 has been substantially entirely emptied of water.

A stop member 69 is carried by the float arm 30 and extends downwardly therefrom so as to limit the downward swinging of the locking member 66 at the time the intermediate float 29 rises after being released from the locking member 42. The feeding tank 14 is connected to a supply tank 70 which is disposed above the feeding tank and which is connected by means of a pipe 71 to a source of water supply under pressure. A float operated valve 72 is interposed in the pipe 71, being actuated by means of a float 73 disposed in the tank 70 for closing the valve 72 when tank 70 is substantially filled.

The tank 70 is connected by means of a pipe 74 to the bottom of the feeding tank 14 and a check valve 75 is interposed in the pipe 74 for preventing flow of water under pressure from feeding tank 14 to supply tank 70. A manually operated valve 76 is also interposed in pipe 74 and a solenoid operated valve 77 is interposed in pipe 74 between manual valve 76 and check valve 75. The solenoid or electrically operated valve 77 is connected by means of a pair of conductors 78, 79, to a float operated circuit maker and breaker 80 of conventional construction which is connected by means of a pipe 81 to the pipe 82 with which the gage glass 11 is connected.

The supply tank 70 also has connected thereto a pipe 83 which is adapted to be connected to the condenser for returning condensate from the elements associated with the boiler and receiving steam therefrom. In order to provide a means whereby water may be raised to the supply tank 70 in the event the pressure in the supply line 71 fails, I have provided a second feeding member generally designated as 14a, which is identical with the construction shown in Figures 2 and 3. The auxiliary low pressure member 14a is disposed below feeding member 14 and is connected by means of a pipe 84 to a source of low pressure water supply. Live steam is supplied to the top of auxiliary feeding member 14a by means of a pipe 85 which is connected at one end to the feeding member 14a and is connected at the other end to steam pipe 49.

An exhaust pipe 86 is connected to the top of the auxiliary tank 14a and the pipe 86 is connected with exhaust pipe 58. Pipe 86 is extended upwardly and horizontally as at 87 and is then connected to a preheating coil which is extended through a boss 88 carried by the supply tank 70 and then extended interiorly of tank 70. A return pipe 89 extends from the heating coil and returns the steam to the auxiliary or low pressure supply member 14a. A check valve 90 is interposed in the pipe 89 to prevent the return flow of steam from feeding member 14a through pipe 89 to supply tank 70.

In the use and operation of this feeding unit or system, water from supply tank 70 is permitted to gravitationally flow into feeding tank 14 by opening of valve 76. The supply of water however, will not flow into tank 14 until electric valve 77 has been moved to an open position. When this electric valve is open, water from tank 70 may flow into tank 14. As tank 14 fills, floats 26, 29 will be urged upwardly by their buoyancy and will be locked against initial upward movement by means of locking member 42 operatively connected to upper float 33. After the tank 14 has

been substantially filled with water, float 33 will rise moving locking member 42 to a released position so that intermediate valve operating float 29 may rise and thereby move steam valve 48 to an open position.

With steam valve 48 open there will be an equalization of pressure in tank 14 on the water so that the water may thereby freely flow from tank 14 past check valves 19, 18 respectively. The intermediate valve controlling float 29 will be held in its uppermost valve opening position by means of the lower locking member 66 which engages the roller 67 carried by the float arm 21. In this manner the steam valve 48 will be held open until the tank 14 has been substantially emptied of water.

When the float 26 loses its buoyancy by the fall of water, roller 67 will be moved away from lower locking member 66 so that the valve operating float 29 and lever arm 30 may drop downwardly to a position where the steam valve 48 is closed and the exhaust or vent valve 57 is opened. The tank 14 is then ready for the second filling operation which will continue in the event the boiler 10 can receive the second or additional feeding tank full of water.

In the event the pressure of water in the supply line 71 is substantially nil so that no water will flow from pipe 71 into tank 10, water from a low pressure supply may be discharged into tank 10 from low pressure supply line 84. The buoyant valve operating means in tank 14a, which is similar to the structure shown in tank 14, will when tank 14a is full, open the steam valve to tank 14a permitting live steam to enter the top of tank 14a from steam line 85. This steam pressure will thereupon force the water in tank 14a through a pipe 91 which is connected at its lower end to tank 14a and at its upper end to tank 10. A check valve 92 is interposed in pipe 91 to prevent return flow of water from tank 10 to tank 14a.

With a feeding means for the boiler as hereinbefore described, the boiler is automatically fed with water when the boiler water drops to a predetermined point and this construction thereby eliminates any injection pump with the leaking glands which are associated with such pumps. This feeding means will prevent the water in the boiler from becoming completely exhausted so that there will not be any danger of burning of the boiler plate or exploding of the boiler due to exhaustion of the water therein.

What I desire to claim is:

1. A water feeding means for a boiler comprising in combination a steam boiler, a feeding tank above said boiler, venting means for said feed tank, a steam pipe connecting said tank with said boiler, a water discharge pipe connecting said tank with said boiler, a check valve in said latter pipe, a valve interposed in said steam pipe, said latter valve including a stem projecting into said tank, buoyant means in said tank connected with said stem for opening said second valve when said tank is substantially filled and for closing said second valve when said tank is substantially empty, a water supply pipe connected to said tank, a check valve in said supply pipe, an electrically operated valve interposed in said supply pipe, float actuated means operatively associated with said electrically operated valve and responsive to the water level in said boiler whereby to effect filling of said tank when the water level in the boiler lowers to a predetermined point, and means connecting said

buoyant means and said venting means for operating said venting means simultaneously with and opposite to said valve in said steam pipe.

2. A water feeding means for a boiler comprising in combination a steam boiler, a feeding tank above said boiler, a steam pipe connecting said tank with said boiler, a water discharge pipe connecting said tank with said boiler, a check valve in said latter pipe, a valve interposed in said steam pipe, a water supply pipe connected to said tank, a check valve in said supply pipe, an electrically operated valve interposed in said supply pipe, buoyant circuit closing means connected with said latter valve and responsive to the water level in said boiler, an exhaust valve connected to said tank, buoyant operating means for said steam valve in said tank, and means connected with said latter buoyant operating means for opening said exhaust valve when said steam valve is closed, and for closing said exhaust valve when said steam valve is open.

3. A water feeding means comprising a steam boiler, a water tank above said boiler, a steam pipe connecting said boiler with said tank, a water discharge pipe connecting said tank with said boiler, a check valve in said discharge pipe, a steam valve connected to said steam pipe and communicating with said tank, buoyant valve operating means in said tank connected to said steam valve and adapted to open said steam valve when said tank is substantially filled and to close said steam valve when said tank is substantially empty, said buoyant means including means rendering said buoyant means inactive until said tank has been substantially filled, and said buoyant means also including means holding said valve open until said tank has been substantially emptied, a vent valve communicating with said tank, an operative connection between said vent valve and said buoyant means for opening said vent valve when said tank is substantially empty and said steam valve is closed, means discharging water into said tank, a check valve in said last mentioned means, and regulating means for said latter means for regulating the discharge of water into said tank according to the water level in said boiler.

4. A water feeding means comprising a steam boiler, a water tank above said boiler, a steam pipe connecting said boiler with said tank, a water discharge pipe connecting said tank with said boiler, a check valve in said discharge pipe, a water supply pipe connected to said tank, a check valve in said supply pipe, an electric valve interposed in said supply pipe, buoyant regulating means carried by said boiler and connected to said valve for effecting opening and closing of said valve according to the boiler water level, a steam valve carried by said tank connected to said steam pipe and including a stem projecting into said tank, a buoyant operator for said steam valve in said tank connected to said stem, said operator including means in said tank correlated with said operator for locking the latter against valve opening operation until said tank has been substantially filled with water and vent means correlated with said operator for venting said tank when the latter is substantially empty and said steam valve is closed.

5. A water feeding means comprising a steam boiler, a water tank above said boiler, a steam pipe connecting said boiler with said tank, a water discharge pipe connecting said tank with said boiler, a check valve in said discharge pipe, a water supply pipe connected to said tank, a

check valve in said supply pipe, an electric valve interposed in said supply pipe, buoyant regulating means carried by said boiler and connected to said valve for effecting opening and closing of said valve according to the boiler water level, a steam valve carried by said tank connected to said steam pipe, a buoyant operator for said steam valve in said tank, means correlated with said operator for locking the latter against steam valve closing operation until said tank has been substantially emptied and vent means correlated with said operator for venting said tank when the latter is substantially empty and said steam valve is closed.

6. A water feeding means comprising a steam boiler, a water tank above said boiler, a steam pipe connecting said boiler with said tank, a water discharge pipe connecting said tank with said boiler, a check valve in said discharge pipe, a water supply pipe connected to said tank, a check valve in said supply pipe, an electric valve interposed in said supply pipe, buoyant regulating means carried by said boiler and connected to said valve for effecting opening and closing of said valve according to the boiler water level, a steam valve carried by said tank connected to said steam pipe and including a stem projecting into said tank, a buoyant operator for said steam valve in said tank, an operative connection in said tank between said stem and said operator, means correlated with said operator for locking the latter against steam valve closing operation until said tank has been substantially emptied, an exhaust valve connected to said tank, and means effecting opening and closing operation of said exhaust valve simultaneously and oppositely with the opening and closing of said steam valve.

7. A water feeding means comprising a steam boiler, a water tank above said boiler, a steam pipe connecting said boiler with said tank, a

water discharge pipe connecting said tank with said boiler, a check valve in said discharge pipe, a water supply pipe connected to said tank, a check valve in said supply pipe, means for venting said tank, an electric valve interposed in said supply pipe, buoyant regulating means carried by said boiler and connected to said valve for effecting opening and closing of said valve according to the boiler water level, a steam valve carried by said tank connected to said steam pipe, a buoyant operator for said steam valve in said tank, means in said tank correlated with said operator for locking the latter against valve opening operation until said tank has been substantially filled with water, said latter means including a buoyant member, a rock lever fixed to said buoyant member, a pivoted locking member for locking said buoyant operator against valve opening movement, and buoyant release means connected between said rock lever and said locking member for effecting movement of the latter to released position after the tank has been substantially filled, said vent means being correlated with said buoyant operator for venting said tank when the latter is substantially empty and said steam valve is closed.
